DESIGN FOR AN OVERHEAD WHIRLING TOY

Philip Di Lemme, New York, N. Y.

Application January 17, 1947, Serial No. 136,213

Term of patent 3½ years

(Cl. D34—15)

To all whom it may concern:

Be it known that I, Philip Di Lemme, a citizen of the United States, residing at the Borough of Bronx, in the county of Bronx, city and State of New York, have invented a new, original, and ornamental Design for Overhead Whirling Toy, of which the following is a specification, reference being had to the accompanying drawing, forming part thereof.

Fig. 1 is a top plan view of an overhead whirling toy, showing my new design.

Fig. 2 is a front elevational view thereof.

Fig. 3 is a side elevational view thereof.

I claim:

The ornamental design for an overhead whirling toy, substantially as shown.

PHILIP DI LEMME.
